ABSTRACT: An assembly for dispensing portions of a gaseous vapor and including a valving body having a dispensing conduit, which is opened and closed by means of a solenoid-actuated plunger contactable with a valving diaphragm. As the solenoid reciprocates the plunger, pressure is relieved upon the adjoining valving pin which, in turn, enables gaseous pressure to urge the diaphragm away from the dispensing conduit permitting gaseous flow.

SOLENOID ACTUATED VALVE

CROSS-REFERENCES TO RELATED APPLICATIONS

An improvement upon the solenoid-activated dispensing device disclosed in U.S. Pat. 3,209,950 entitled AUTOMATIC DISPENSING DEVICE.

In U.S. Pat. 3,209,950 the solenoid was employed to activate a valve from closed to open position. In the present construction, the valve is held closed by tension of a compression spring within the solenoid assembly. As the solenoid reciprocates the plunger, pressure is relieved upon the adjoining valving pin allowing the diaphragm to be urged away from the dispensing conduit by means of gaseous pressure. The valve, being in the open position, gaseous flow is instigated and maintained until such time as solenoid is deactivated.

BACKGROUND OF THE INVENTION:

1. Field of the Invention

A great deal of recent attention has been given to automatic and intermittent dispensing of gaseous fluids, such as insecticides, for example, the dispensing of insecticides in a tobacco warehouse or public enclosures such as restaurants and auditoriums.

2. Description of the Prior Art

Earlier inventors have developed fluid dispensers in which the nozzle and valve mechanisms are actuatable by a clock mechanism or a solenoid. Prior art searching has developed:

Kraus 2,613,108

Gubelin 2,686,944

Edlestein 2,928,573

Kus 3,189,014

The present invention is distinguished from these in the simplified, strengthened, and improved structure for the valving mechanism and including the solenoid-actuated plunger contactable with a valving diaphragm.

SUMMARY OF THE INVENTION

According to the present invention, the solenoid-actuated valve assembly includes a valving body having a fluid-flow conduit extending therethrough, a valving seat defined medially of the body so as to intersect the fluid-flow conduit. A diaphragm is supported upon the seat so as to intersect the conduit and a solenoid-actuated plunger is supported above the diaphragm so as to hold the diaphragm closed and intersecting the conduit, except as the plunger is released. As the plunger is released, the superatmospheric pressure of the gas urges the diaphragm to open the conduit, so long as the plunger is removed from the diaphragm. As the plunger closes against the diaphragm, the conduit is intersected and gaseous flow is cut off. Positive cutoff is effected by directing the conduit axially beneath the diaphragm and having an axial plunger engageable on the other side of the diaphragm so as to urge an axial portion of the diaphragm into the conduit.

BRIEF DESCRIPTION OF THE DRAWINGS

FIG. 1 is a perspective view of the solenoid valve assembly, showing the solenoid-actuated plunger unit secured to the valving body;

FIG. 2 is an exploded perspective view of the valving body and plunger components;

FIG. 3 is a vertical section of the valving body with the solenoid assembly superposed with respect thereto; and

FIG. 4 is a vertical section of the outlet nozzle adapter.

DESCRIPTION OF THE PREFERRED EMBODIMENTS

In FIG. 1, solenoid unit 10 is shown as secured on top of valving body 12, having inlet 46 and outlet 30.

As illustrated in FIGS. 2 and 3, valving body 12 includes a plurality of vertical apertures 16, 18, 20 and 22 wherein pins (not illustrated) may be used to secure solenoid unit 10 and valving body 12 together.

Valving body 12 includes gaseous fluid-flow inlet 24 and outlet 26. Inlet 24 includes lateral passage 25 into which a stainless steel tube 46 having a drilled axial passage 92 may be press-fitted or otherwise secured therein. The diameter of axial passage 92 may be of a constant size such as 0.024 inches, so as to insure constant flow rate and particulate size. Outlet 26 includes interior threads 42 for engagement with exterior threads 40 upon adapter nozzle 28. Adapter nozzle 28 includes axial conduit 84, terminating in a radially outwardly tapered area 86. A monel or like fine mesh strainer 32 may be secured adjacent area 86 by means of threaded cap 30. Cap 30 has radially inwardly extending flange 88 abutting outer shoulder 90 adapter nozzle 28. Screen 32 may be held in compression by threaded engagement with another conduit not shown.

The gaseous fluid-flow conduit is defined by tube 46 in lateral inlet 25, vertical entry passage 48, horizontal valving seat chamber 27, vertical exit passage 52, and lateral exit chamber 54.

20 Illustrated in FIG. 3, Teflon valving diaphragm 62 which inherently passes some of said gaseous fluid by osmosis rests upon annular shoulder 60 enclosed by upstanding wall 56 in the body top 58. A Neoprene or like diaphragm 64, having substantial strength to reinforce valving disc 62 and including a vent hole 66 is secured coextensively upon diaphragm 62, by means of an aluminum or like rigid backup plate 68 having hub 70 and axial passage 72.

25 Valving pin 74 is supported reciprocably in passage 72, so as to contact that portion of the diaphragms 62-64 registering with axial passage 52. A compression spring 76 is fitted within walls 56 so as to abut the top of backup plate 68 at its lower end and its top abutting the bottom of solenoid assembly housing 10. A solenoid assembly mounted within housing 10 includes a reciprocable plunger 80 which may be made of stainless steel or the like and have an axial recess 94 at its top for supporting compression spring 82. Plunger 80 may include, at its bottom, tip 78, made of Neoprene or the like, so as to be replaceable as it wears in reciprocating contact with pin 74 and eliminating the necessity for change of the entire solenoid and plunger assembly.

30 The device is constructed such that plunger 80 in normal position closes downwardly against pin 74 so as to close exit passage 52. As it is desired to eject fluid or gaseous spray through the outlet, the solenoid retracts plunger 80, permitting the pressure of the gas to flex the diaphragm and open the conduit for flow through vertical entry passage 48, chamber 27, vertical exit passage 52, and lateral conduit 54. The solenoid may be activated in this respect by any one of a 35 number of conventional timing devices.

35 The reverse taper radially outwardly expanding chamber 86 in nozzle adapter 28 prevents dripping of liquified chemicals. The manufacture of the valving body in a single piece eliminates the leakage inherent in conventionally articulated 40 valve housings. Venting of Neoprene disc 64 avoids trapping of gases which can rupture the diaphragms 62-64. The use of a continuous duty solenoid, as opposed to an intermittent duty solenoid, avoids the damage inherent in accidental activation by the assembly.

45 Manifestly, the valving body orifice and diaphragm structure may be modified without departing from the spirit of the invention.

We claim:

1. A solenoid actuated valve comprising:
  - A. a valve body enclosing a fluid flow conduit having inlet and outlet ports in said body and said valve body including:
    - i. a valving seat communicant with said conduit;
    - B. said conduit extending laterally from said inlet, vertically towards and away from said valve seat and laterally through said outlet and said valving seat including:
      - i. an annular shoulder for supporting the periphery of said diaphragm as a top seal above a valving chamber;
      - ii. an axial hub extending upwardly from the bottom of said valve chamber;

- iii. a fluid-flow entry passage extending vertically from said conduit into said valving chamber; and
- iv. a fluid-flow exit passage extending vertically through said axial hub from said valve chamber to said conduit;
- C. a resilient diaphragm supported in said valving seat, so as to intersect said conduit, so as to be sealed upon said annular shoulder and contacting said exit passage in said hub, said diaphragm being resiliently responsive to the pressure of fluid flowing in said conduit so as to open said conduit;
- D. a solenoid assembly supported upon said body adjacent said diaphragm and including:
  - i. a reciprocable plunger assembly engaging said diaphragm on the opposite side of said conduit, said plunger assembly urging said diaphragm to close said conduit and permitting said diaphragm to open said conduit responsive to gas pressure, as said plunger is released;

- ii. a rigid backup plate having a vertically disposed core defining an axial aperture aligned with said exit passage;
- iii. a resilient reinforcing plate secured coextensively between said diaphragm and said backup plate and having a vent hole;
- iv. a pin supported in said aperture so as to extend through said backup plate aperture to engage said resilient plate at its lower end and engage said plunger at its upper end; and
- E. a compression medium supported in said valve body intermediate said backup plate and said solenoid assembly, including a spring encircling said plunger and said hub and seated upon the periphery of said backup plate above said diaphragm, so as to urge the periphery of said diaphragm onto said annular shoulder.
